UNITED STATES PATENT OFFICE.

JOHN BOWEY, JR., OF LONDON, ONTARIO CANADA.

SUCTION GAS-PRODUCER.

No. 893,604.

Specification of Letters Patent.

Patented July 21, 1903.

Application filed September 23, 1902. Serial No. 394,100.

To all whom it may concern:

Be it known that I, JOHN BOWEY, Jr., a citizen of the Dominion of Canada, residing at London, in the county of Middlesex and Province of Ontario, Canada, have invented new and useful Improvements in Suction Gas-Producers, of which the following is a specification.

My invention relates to suction gas producers in which air and water in the form of steam are drawn into the producer by the suction of the piston of the engine on its charging stroke and my object is to devise means for automatically proportioning the quantity of water used to the rate of consumption of gas and for similarly controlling the rate of elimination of the ashes.

In my apparatus I use the expansive force of the hot exhaust to operate a valve in a water tank and also to effect a partial rotation of the grate of the producer. The water flows through an open spiral trough in an annular chamber at the top of the producer where it is converted into steam before introduction into the air supply. Thus, at every exhaust stroke of the engine water is measured and a certain quantity of ashes eliminated and on the charging stroke the steam and air are drawn into the producer. As these operations occur at every cycle of the engine the introduction of air and steam and the elimination of ashes varies with the speed of the engine and consequently the rate of production of gas varies with the demand of the engine which depends on its speed.

Figure 1 is a front elevation of my device partly in section. Fig. 2 is a plan view of the same. Fig. 3 is an enlarged detail in elevation of the lower part of the producer showing the automatic shaking device. Fig. 4 is a detail in vertical section of the lower part of the producer at right angles to Fig. 3. Fig. 5 is an enlarged section of the detail of the water tank and connected parts. Fig. 6 is a plan view of Fig. 5.

In the drawings like letters of reference indicate corresponding parts in the above figures.

1 is the body of the producer preferably formed of a steel shell lined with suitable refractory material. This producer is provided at the bottom with the boshes 37 and below the boshes is mounted the rotatable

32 grate of the conical shape shown. The grate is provided with a stem or shaft 30, the lower end of which is journaled in the upper end of the screw shaft 34. The shaft 30 also has a bearing in the upper end of the conical center 59 of the ash receptacle 38 which is partly filled with water into which the lower end of the producer extends to form a water seal for the ash chamber. The screw shaft 34 is threaded into the sleeve 35 and is provided with a hand-wheel 36 by which it may be turned. This hand-wheel may be reached through a hand-hole 58. It is evident that by turning the hand-wheel that the grate may be vertically adjusted to vary the annular aperture between it and the boshes. Means hereinafter described are provided for automatically rotating the grate. Through the top of the receptacle extends the feeding hopper 2 preferably, though not necessarily, of the pear shape shown. A charging chamber 3 is provided at the top of the feeding hopper. The outlet of this charging chamber is closed by means of an ordinary cone-shaped valve 4 operated by means of a counter-balanced lever 5. A movable cover 6 is provided of cylindrical shape which projects into the annular trough 7 filled with water to form a water seal. The bottom of the feeding hopper projects into the top of the producer. Within the top of the body of the producer about the feeding hopper is an annular chamber 8 which forms a vaporizer. This chamber is provided with an air inlet 10 and has an outlet pipe 11 communicating with the ash chamber of the producer. Within the chamber 8 and out of contact with its walls is placed an open helical trough 9. A funnel shaped casting 55 extends into the interior from without and is adapted to discharge into the upper end of the helical trough. It is evident from this construction that any water conveyed to the trough is converted into steam which is subsequently superheated by coming into contact with the heated walls of the vaporizer. The air supply is drawn in through the inlet 10, mingles with the steam, is pre-heated, and with the steam is drawn through the pipe 11 to the ash chamber, thence passing through the

105 fuel to the combustion zone of the producer.

The gases resulting from combustion circulate between the walls of the feeding hopper and the vaporizer 8 heating the latter and pre-heating the fuel in the former. The

gas escapes through the pipe 15 which leads out through the vaporizer and is connected with the scrubber 12 which is of any ordinary construction.

As stated in the preamble of the specification I have devised means for automatically regulating the rate of supply of water and the rate of elimination of the ashes and I will now describe this mechanism. The

10 water is supplied from the tank 47 into which water is led through a suitable pipe provided with the valve 48 which serves to maintain the water at a constant level and shuts off the supply when the producer is not in operation. In the bottom of the tank 47 is an opening 49 controlled by a slide-valve 50. The valve rod 51 is connected to the slide and projects through the wall of the tank. This valve rod is operated by means of the 15 lever 42 which is pivoted intermediate its ends on the bracket 43. The valve rod 51 passes through the end of the lever 42 and collars 46 are screwed upon the rod at each side of the lever 42. A collar 57 is also secured to the rod 51 and the coil spring 53 bears against this collar and against the bracket 54 which forms a bearing through which the rod 51 may slide. This spring tends to retain the slide valve in its closed 20 position. From this construction it follows that by rocking the lever 42 the slide valve may be opened to allow water to escape to the vaporizer, the extent to which the valve is opened by any given movement of the 25 lever 42 depending on the position of the collars 46 which may be adjusted on the valve rod to give any desired opening of the valve.

I have arranged means whereby the lever 42 is automatically rocked by the exhaust of 30 the engine. For this purpose I provide a cylinder 16 closed at each end and provided with the inlet pipe 17 at one end and the outlet pipe 18 at the other. The rod 19 extends axially through the cylinder and is 35 longitudinally movable therein. To this rod is secured the diaphragm 20 situated close to the end of the cylinder opposite the inlet pipe. This diaphragm does not closely fit the walls of the cylinder so that an escape 40 is provided for gases passing the diaphragm. On the rod 19 outside the cylinder adjacent to the inlet pipe is placed a coil spring 21 which bears against the end of the cylinder and against the collar 22 secured upon the 45 rod. This spring tends to maintain the diaphragm in the position shown in full lines in Fig. 1. The opposite end of the rod 19 is connected to an arm 23 by means of a pin 27 engaging the slot in the end of the arm and 50 is pivoted at one end on the shaft 24. This arm 23 carries a pawl 25 which engages the teeth of a ratchet wheel 26 which is secured to the shaft 24. The shaft 24 is suitably 55 journaled in the ash receptacle and is provided at its inner end with a bevel pinion

28 which meshes with the bevel gear 29 which is connected with the grate shaft 30 by a feather key and key way 31. (See Fig. 4.) From this construction it follows that when the gases from the exhaust of the engine enter the cylinder 16 through the pipe 17 the sudden expansion of the gas forces the diaphragm 20 forward thus giving a partial rotation to the ratchet wheel 26 by means of the rod 19 and pawl 25. As the explosive force of the liberated gas is only momentary the spring 21 immediately draws the diaphragm back to its original position.

The rotary motion imparted to the ratchet wheel 26 is transmitted to the grate 32 through the shaft 24 by means of the bevel pinion 28 and the bevel gear 29. The resulting rotary motion causes the ashes to work down between the grate and the bosh walls and through the aperture in the grate. When the load on the engine increases and the explosions becomes more frequent the grate is rotated proportionately more frequently, keeping the fire clean for all conditions of load.

The rate at which the ashes are ejected is controlled by raising or lowering the grate by means of the hand-wheel 36. Owing to the feather key connection of the bevel gear 29 with the shaft 30 this adjustment of the grate in no wise interferes with its rotary motion.

In order that the exhaust may operate the water feeding valve 50 the lower end of the lever 42 is brought down to a convenient point and the rod 19 passed through it. Adjustable screw collars 40 are placed on the rod 19 on each side of the lever 42 for the purpose of adjusting the contact between the two, thus, each time the grate is partially rotated the lever 42 is moved to cause a feeding of water to the vaporizer as hereinbefore described so that the water feeding, similar to the ash elimination, corresponds exactly to the demands made upon the producer by the engine. It should be stated that the producer is supported by legs 57, the feet of which rest in the ash receptacle.

What I claim as my invention is:

1. A gas producer; a source of water supply therefor; a valve controlled outlet for the water supply; and ash eliminating means, in combination with an internal combustion motor and means operable by the exhaust of the motor for operating said valve and said ash eliminating means.

2. A gas producer; and ash eliminating means therefor in combination with an internal combustion motor; and means whereby the motor intermittently operates the ash eliminating means at some part of each complete cycle of the motor.

3. A gas producer; and ash eliminating means therefor in combination with an internal combustion motor; and means whereby

the exhaust of the motor operates the ash eliminating means.

4. A gas producer; a source of water supply therefor; a valve controlled outlet for the 5 water supply; and ash eliminating means, in combination with an internal combustion motor, means operable by the exhaust of the motor for operating said valve and said ash eliminating means, means for regulating the 10 flow through the valve, and means for regulating the discharge of the ash eliminating means.

5. A gas producer; a source of water supply; means for controlling the flow therefrom; and ash eliminating means, in combination with an internal combustion motor; and means whereby the motor operates the ash eliminating means and the water control at some part of each complete cycle of the 20 motor.

6. A gas producer; a source of water supply; and ash eliminating means, in combination with an internal combustion motor taking its gas supply therefrom, and means 25 whereby the motor causes the water to be supplied and ashes eliminated at a rate de-

termined by the gas consumption of the motor.

7. A gas producer; a rotatable grate therefor; a shaft to which said grate is secured; a 30 screw shaft on the end of which the grate shaft is journaled; a sleeve into which the screw shaft is threaded; a gear wheel having a feather key and a key way connection with the grate shaft; and a hand wheel on the 35 screw shaft.

8. An internal combustion motor in combination with a cylinder provided with an inlet at one end, connected with the exhaust of the engine, and an exhaust outlet at the 40 other; a spindle longitudinally slidable in the cylinder; a diaphragm secured to the spindle and arranged to permit of an escape of gas from one side thereof to the other; and a spring tending to maintain the parts in their 45 normal position.
